UNITED STATES PATENT OFFICE.

WILLIAM JAMES TIFFANY, OF BROCKTON, MASSACHUSETTS.

METHOD OF AND TOOL FOR REPLACING BROKEN HAMMER-BUTT SPRINGS.

Application filed July 15, 1922. Serial No. 575,398.

To all whom it may concern:

Be it known that I, WILLIAM J. TIFFANY, a citizen of the United States, residing at 93 High Street, Brockton, Massachusetts, have invented certain new and useful Improvements in Methods of and Tools for Replacing Broken Hammer-Butt Springs, of which the following is a specification.

This invention relates to piano actions, and particularly to a method of and tool for replacing broken hammer butt springs in an upright piano action.

The usual butt spring consists of a length of wire having a coil between its ends to give the spring its resiliency, a straight fastening end which is attached to the hammer spring rail of the piano action and an upturned bearing end which bears against the hammer butt to return the hammer after it has been projected against the piano string by the depression of the key. In the usual upright piano action, the fastening ends of the springs are drawn through small holes drilled in the spring rail when the piano action is assembled.

The replacement of these springs, when broken, is a matter of considerable difficulty, due to their general inaccessibility after the piano action has been assembled. The physical presence of the hammers and other parts of the piano action, and the particular manner in which the original springs are mounted in the spring rail are all factors which make the replacement of a broken spring by the usual methods a long, tedious task involving removal of the spring rail, and often times other parts as well of the piano action.

Moreover, the replacement spring is apt to be unsatisfactory because of the difficulty of drawing up the spring tightly in the hole of the spring rail. Where the spring is loosely attached, it will wobble relative to the hammer which it is supposed to return and will not return the hammer promptly.

To the end therefore of overcoming these objections I have devised my present invention. According to my invention, the replacement springs are tacked to the spring rail instead of being threaded through the holes in said rail, as has been the previous practice. In carrying out my invention I provide a novel form of tool for initially forming a tack holding loop in the replacement spring and for subsequently as-

sembling said formed spring and its attaching tack in position for attachment to the spring rail.

As contemplated herein, such tool comprises a pair of crossed handle members having oppositely disposed forming and assembling jaws. The replacement spring is temporarily mounted upon the forming jaw of the tool, by lodging its spring coil over a retaining pin on said jaw, and is then bent around an anvil on said jaw to form between the ends of the spring a tack holding loop. The formed spring is then transferred to and releasably lodged upon the assembling jaw of the tool, by lodging its spring coil over a retaining pin on said jaw, a tack is inserted in said tack holding loop, and the free end of the spring is temporarily clamped beneath a spring clip on said jaw. The jaws are then laid against opposite faces of the piano spring rail and when brought towards each other will press the tack firmly and accurately into the wooden spring rail at the desired point. The end of the spring anchored under said clip is then disengaged by a sidewise freeing movement of the tool, leaving the spring accurately tacked in place upon the spring rail of the piano action.

By my invention, it is possible to work from the front of the piano action between the hammer stems at any desired point without removing the hammer spring rail or any other part of the action from the piano. The spring, moreover, is securely fastened in position and will not wobble relative to its hammer, as usually happens when a spring is replaced by the old method. The tool itself is of simple inexpensive construction and light weight and conveniently fits within the usual piano tuner's kit roll.

The manner of practicing my invention together with a form of tool and replacement spring which I have found satisfactory in use, are described and illustrated in the accompanying specification and drawings and the characteristic features of novelty are particularly pointed out in the appended claims. Throughout the specification and drawings like reference characters are correspondingly employed.

Fig. 1 is a partial vertical section through the piano action of an upright piano and indicating the use of my device.

Fig. 2 is an elevation of my device.

Fig. 3 is an end view thereof.

Figs. 4 and 5 are detail views illustrating the manner of use of the device in forming a replacement spring.

Fig. 6 is a view of the usual hammer butt spring, and

Fig. 7 is a view of a replacement spring after it has been bent to form the tack holding loop in accordance with my invention.

I have indicated at 1, Fig. 1, the hammer 10 stem rail of an upright piano action of standard type, at 2 the hammer spring rail, at 3 a hammer stem, at 4 the hammer butt, at 5 the hammer shank, at 6 the back stop and at 7 the usual hammer butt spring 15 which is fastened at one end 8 to the hammer spring rail, usually by threading said end through a hole drilled in said rail, and at its opposite end 9 bears against the hammer butt 4, and between its ends is provided with a coil 10 to give resiliency to the spring. According to my invention, the replacement springs are tacked to the hammer spring rail at the proper points, rather than being drawn through the usual holes drilled 20 in the rail, as has been the previous practice, thereby obviating the necessity of removing at least the piano spring rail and sometimes other parts of the action, as is necessary with the ordinary repair method, and 25 permitting access to the springs from the front of the piano action without disassembling any part of the action.

I secure these results by means of a novel 30 tool which is at once both a device for forming the spring for attachment to the spring rail and for attaching said spring. As here shown, such tool consists of a pair of crossed handle members 11 and 12 which are pivoted to each other at 13 and are of 35 the general pliers type. At its operative end the handle 11 carries a head or jaw 14 of generally flat rectangular shape and the handle 12 carries a similar head or jaw 15 opposite the head 14.

The head 14 is a forming head and at one 40 corner is provided with a pair of projections 16 and 17 disposed at right angles to each other, or as here shown with a single right-angled pin which is embedded in said head and fastened thereto in any suitable manner.

The head 15 of the handle member 12 is 45 an assembling head and is provided opposite the forming mandrel 16-17 with a centering pin 20, over which the coil 10 of the spring is adapted to be lodged, when the spring is transferred from the head 14 to the head 15 and a tack T lodged in the loop 19, as illustrated in Fig. 4.

In attaching the replacement spring 50 shown in Fig. 6, the coil 10 thereof is temporarily lodged over one of the forming projections 16 and 17 of the head 14, and the free or fastening end 8 of the wire is 55 wrapped around the other of said projec-

tions in a plurality of turns to form the tack holding loop 19. The formed spring is then bodily removed from the head 14 and applied to the head 15 with its coil 10 lodged over the centering pin 20 of said head, the head of a tack T is lodged within the loop 19 of said spring, and the end 8 of the spring is drawn beneath the spring clip 21, whereupon any excess length of wire at the end 8 beyond the tack T may be cut off. The spring and tack are thus releasably clamped in assembled position on the head 15. The tool is next inserted as a pair of pliers against opposite sides of the wooden spring rail 2, as indicated at Fig. 1, and the tack pressed rather than hammered into the under face of said rail. After the tack is set, the repair man dislodges the end 8 of the spring from beneath the spring holding clip 21 and also slides the coil 10 from the centering pin 20 by a lateral freeing movement of the tool as a whole and withdraws the tool from the action. The spring is thus accurately and 75 positively fastened to the spring rail by the tack T which constitutes the sole means of attachment, and the replacement operation has been performed from the front of the piano action without disassembling the action and in considerably less time than is required by the old method of threading the replacement springs through the holes in the spring rail.

Various modifications in the manner of 80 and apparatus for practicing my invention may obviously be resorted to within the limits of the appended claims.

What I therefore claim and desire to 85 secure by Letters Patent is:

1. The method of replacing the hammer 90 butt spring of a piano action which consists in providing the replacement springs with a tack holding portion disposed to releasably retain a tack with its point positioned for penetration into one face of the hammer 95 spring rail of the piano action, in temporarily assembling said spring and tack upon an inserting device, in applying said device to opposite faces of the spring rail to press the tack into one face of said rail, and in 100 disengaging the spring from said device and withdrawing said device from the piano action.

2. The method of replacing the hammer 105 butt spring of a piano action which consists in providing the replacement spring with a tack holding portion disposed to retain a tack with its point positioned for penetration into one face of the hammer 110 spring rail of the piano action, in lodging a tack in said holding portion of the spring, and in pressing the tack while so held into 115 said rail to thereby position the spring upon the rail.

3. The method of replacing the hammer 120

butt spring of a piano action which consists in providing the replacement spring with a tack holding loop disposed to releasably retain a tack at right angles to the 5 plane of the spring, with its point positioned for penetration into one face of the hammer spring rail of the piano action, in lodging a tack in said holding loop of the spring, and in pressing the tack while so 10 held into said rail to thereby position the spring upon the rail.

4. The method of replacing the hammer butt spring of a piano action which consists in bending the spring upon itself to 15 form therein a tack holding loop, in lodging the head of a tack in said loop with its point disposed for penetration into one face of the hammer spring rail of the piano action, and in pressing the tack while so 20 held into said rail to thereby position the spring upon the rail.

5. The method of replacing the hammer butt spring of a piano action which consists in lodging the usual coil of the replacement 25 spring over a centering device, in bending the spring upon itself while so lodged to form therein a tack holding loop, in lodging the head of a tack in said loop with its point disposed for penetration into one 30 face of the hammer spring rail of the piano action, and in pressing the tack while so held into said rail to thereby position the spring upon the rail.

6. A tool for fastening a replacement 35 spring to the hammer spring rail of a piano action, comprising a member having a mandrel over which the spring is adapted to be bent to form therein a tack holding loop, and positioning means for disposing the 40 formed spring with a tack assembled therein in position to be forced into one face of said rail.

7. A tool for fastening a replacement 45 spring to the hammer spring rail of a piano action, comprising a member having a mandrel over which the spring is adapted to be bent to form therein a tack holding loop, and positioning means with which the usual coil of the replacement spring is engageable for disposing the formed spring with a tack assembled thereon in position to be forced into one face of said rail.

8. A tool for fastening to the hammer 55 spring rail of a piano action a hammer butt replacement spring having the usual spring coil between its ends and having a tack holding loop adjacent said coil, comprising a member having a centering pin over which said coil is engageable to dispose the 60 spring with a tack assembled thereon in position to be forced into one face of said rail.

9. A tool for fastening a replacement 65 spring to the hammer spring rail of a piano action, comprising a pair of crossed handle

members having oppositely disposed forming and assembling jaws, said forming jaw having means whereby a tack holding loop may be formed in the replacement spring 70 while said spring is temporarily retained upon said jaw, and said assembling jaw constructed and arranged to receive and releasably clamp the formed spring when it is removed from the forming jaw and a tack inserted into said tack holding loop 75 with its point positioned for penetration into one face of the spring rail when the jaws are applied to opposite faces of said rail and pressed towards each other, said clamping means of the assembling jaw automatically releasing the spring upon a freeing movement of the tool in a lateral direction after the tack has been set in the rail.

10. A tool for fastening a replacement 80 spring to the hammer spring rail of a piano action, comprising a pair of pivoted handle members having oppositely disposed forming and assembling jaws, said forming jaw having means for engaging the coil of the replacement spring to temporarily retain 85 the spring upon said jaw and having means whereby a tack holding loop may be formed in said spring while said coil is engaged, and said assembly jaw having means for engaging the coil of said spring to temporarily retain the spring upon said jaw 90 after it has been removed from the forming jaw and having means for releasably clamping the spring beyond said coil while a tack is inserted into said tack holding loop 95 with its point positioned for penetration into one face of the spring rail when the jaws are applied to the opposite faces of said rail and pressed towards each other, said clamping means of the assembling jaw 100 automatically releasing the spring upon a freeing movement of the tool in a lateral direction after the tack has been set in the rail.

11. A tool for fastening a replacement 105 spring to the hammer spring rail of a piano action comprising a pair of crossed handle members having oppositely disposed jaws, one of said jaws having means to temporarily receive the coil of the replacement 110 spring while a tack holding device is being formed on said spring, and the opposite jaw having means to temporarily receive the coil of the spring when the spring is removed from the first-named jaw and a tack inserted in said tack holding device 115 whereby when the jaws are applied to opposite faces of the hammer spring rail and pressed towards each other the tack lodged in said tack holding device will be forced 120 into said rail.

12. A tool for fastening a replacement 125 spring to the hammer spring rail of a piano action comprising a pair of crossed handle members having oppositely disposed jaws,

one of said jaws having a pair of projections disposed at right angles to each other and over one of which the coil of the replacement spring is adapted to be placed 5 with the body portion of said spring beyond said coil disposed beneath the other projection for twisting movement therearound to provide a tack holding loop in the spring, the opposite jaw having a projection 10 over which the coil of the formed spring is adapted to be centered when removed from the first-named jaw, and a tack inserted in said tack holding loop, whereby when the jaws are applied to opposite faces 15 of the hammer spring rail and pressed towards each other the tack lodged in said tack holding loop will be forced into said rail.

13. A tool for fastening a replacement 20 spring to the hammer spring rail of a piano action comprising a pair of crossed handle members having oppositely disposed jaws, one of said jaws having a pair of projections disposed at right angles to each other 25 and over one of which the coil of the replacement spring is adapted to be inserted

with the body portion of said spring beyond said coil disposed beneath the other pin for twisting movement therearound to provide a tack holding loop in the spring, 30 the opposite jaw having a projection over which the coil of the formed spring is adapted to be centered when removed from the first-named jaw and a tack inserted in said tack holding loop, and having a holding clip under which the free end of the spring beyond the tack holding loop is adapted to be laid whereby when the jaws are applied to opposite faces of the hammer spring rail and pressed towards each other 40 the tack lodged in said tack holding loop will be forced into said rail, the holding clip automatically releasing the spring upon a freeing movement of the tool in a lateral direction after the tack has been set in the 45 rail.

In testimony whereof I affix my signature in the presence of two witnesses.
